Fig. 1

Fig. 2

Fig. 3

FIGURE 1 is a plan view of a tissue dispenser, showing our new design.

FIGURE 2 is a front elevational view of the same.

FIGURE 3 is an end elevational view of the same.

FIGURE 4 is a fragmentary cross-sectional view through the top of the tissue dispenser taken on the line 4—4 of FIGURE 1 showing the configurational detail of the diamond-like pattern.

The end, not shown, is the same in appearance as the end shown. The rear elevation is the same as the front elevation except that the arched cut-out is omitted.

It is to be understood that the diamond-like pattern seen in FIGURE 1 is repeated throughout the area.

We claim:

The ornamental design for a tissue dispenser, as shown and described.
